UNITED STATES PATENT OFFICE.

DANIEL E. MULCAHY AND RAYMOND C. HITT, OF SEATTLE, WASHINGTON.

MACHINE FOR LOADING FIRECRACKERS.

Application filed March 3, 1927. Serial No. 172,461.

This invention relates to machines for loading firecrackers, and particularly firecrackers known as the "flaskcracka" type, wherein the charge is held in a sack in the shell. In the loading of the shells of the flaskcracka type, it has been the custom to place the required amount of explosive in a paper tube or sack which was folded or tied in some simple flexible material which was then compressed into the open shells by hand, a very slow process; and it is among the objects of this invention to provide a machine for rapidly loading the shells, the operator merely depositing the bags in the mouth of suitable tapered holes in a cylinder which revolves until the holes come opposite the mouth of one of shells, at which time a plunger moves forward and compresses the sack into the shell; and thereupon the plunger withdraws till another sack in another hole has been turned adjacent to another shell, when the operation is repeated; the placing of the shells and operation of the different parts of the machine being timed to automatically act at predetermined periods, while parts of the machine move continuously.

A further object is to provide a machine for loading firecrackers, to be operated with parts thereof continuously moving, with other parts moving intermittently, with a hopper for supplying the shells, an endless belt with buckets and a chute therefrom for conveying the shells to grooves in the periphery of a drum, with a cylinder mounted adjacent to one end of the drum, with holes through the cylinder registering with the grooves on the drum, and a plunger mounted to be operated with a reciprocal motion through the holes over a portion of the respective grooves, the drum and cylinder each supported on separate axles and connected by gears to rotate at the same time, with a ratchet wheel mounted on the axle of the drum and a pawl operated by the plunger, to turn the ratchet at intermittent periods, for discharging the shells when loaded and bringing into proper position the next and successive shells for loading, together with other objects hereinafter set out.

We have illustrated our invention by the accompanying drawings, of which:

Figure 1 is an end elevation, Figure 2 is a top plan; Figure 3 a rear elevation in section taken on line 3 of Figure 2, with parts

broken away; and Figure 4 is a detail view of the ratchet and its operating means.

Like numerals on the different figures represent like parts. 1 is a supporting frame, with connection 2 for permitting adjustment of the part 3 of the frame for different lengths of the drum 4 which is fixed to and revolves with its axle 5. The drum is provided with a series of grooves 6 at determined spaces apart around its periphery, with a flange 7 at one end for retaining the tubular firecracker shells 8. A cylinder 9 is mounted adjacent one end of the drum, with a series of holes 10 therethrough and sloping mouths 11, for the easy insertion of the bags 12 containing suitable explosive material and protruding fuses 13. The cylinder is attached to an axle 14 which is turned by a gear wheel 15 attached to axle 5, meshing in gear 16 on the periphery of the cylinder, the gear 16 being double the diameter of the gear 15, and turning the cylinder twice while the drum turns once.

A loading plunger 17 is slidably mounted in a tube 18 in frame 1. The end of plunger adjacent the cylinder is reduced in size as 19, and is reciprocated in the tube by a connecting rod 19 attached by a pivot pin 20, the outer end of the rod is connected by an adjustable pin 21 (to determine the length of stroke) with a crank 22 affixed to the power shaft 23 supported by posts 24 and 25, and driven by any suitable motor or pulley 26 and belt 27, the shaft held on the posts by suitable journal boxes 28 and 29.

The drum and cylinder are intermittently turned as the plunger operates by blocks 30 and 31 adjustably attached to the plunger, and which alternately move a lever 32 which is provided with a yoke 33 at its top through which the plunger freely slides, till the blocks strike the lever, when the latter is tripped on its fulcrum pin 33 held by bracket 34. The lower end of lever 32 is connected by pivot pin 35 with shift rod 36, the other end of the rod is attached by pivot pin 37 to lower end of a bell crank 38 mounted on pivot pin 39 to the frame 1. The other end of the bell crank is pivotally attached to the top end of a link 40, with the lower end of the link attached by a pivot pin 41 to a collar 42 which is adjusted over the outer bend of a yoke 43 and permits that part of the yoke to turn in the collar as the link is raised or lowered by the motion of the bell crank. The two ends 44 of the yoke

are bent around the axle 5 and turn freely thereon as the link is raised or lowered, a ratchet wheel 45 is attached to the axle 5 between the ends of the yoke, and a pawl 46 5 is freely mounted at its outer end on an axle 47 attached to and between the arms of the yoke; with the inner end of the pawl adjusted to turn the ratchet wheel as the yoke is raised by the crank, but to ride down and 10 over the ratchet teeth when the crank lowers the yoke. The pawl may be further controlled by a spring.

The empty tubular firecracker shells are deposited in a hopper 48 and thence carried 15 up by an endless belt 49 and buckets 50 operated over a top pulley 51 driven by shaft 52, the belt passing thence down and around a loose pulley 53, on shaft 53^a positioned at the lower edge of the hopper, the latter being 20 provided with an opening at the base to permit the belt and buckets to pass therethrough, to pick up the empty shells as the buckets move up through the hopper. As the buckets turn down over the top pulley 25 51 the shells drop therefrom into a chute 54 and roll down the same to and against the drum 4. As the latter is revolved the successive lower shells drop partly into the grooves 6, and below the top guards 55 of the chute, 30 and are then carried by the drum to a position opposite one of the holes 10 through the cylinder 9, in front of the tube 18 and point of plunger 19; in which position the drum is held by a spring 56 with a slidable shoulder 35 57 which drops into the adjacent groove 6, as the pawl has then reached its highest position with the plunger point 19 drawn back free from the cylinder. The mouths of the holes through the cylinder are of sufficient 40 diameter to permit the operator to readily insert the bags 12 of explosive, with the fuse protruding, and as the crank 22 forces the plunger on against the bag in the adjacent hole 10, the bag is carried by the narrowed 45 point 19 of the plunger clear through the hole in the cylinder and on into the firecracker shell lying in the groove 6 opposite the point of the plunger. As the holes 10 in the cylinder are of the same diameter as the 50 holes in the shells at the end where they meet, but larger at their mouths, the bags are compressed by the tapering hole to proper size to fit tightly inside the walls of the shell, and require no clay or other means for holding the explosive in the positions in the shells. The shell when being loaded is held 55 in position against the force of the plunger by the flange 7 across the outer end of the grooves.

60 As the plunger is moved into its forward position the block 30 comes into contact with the lever 32 and forces the pawl down to its lower position on the ratchet, and when the plunger has been again withdrawn from the 65 cylinder the block 31 contacts with the lever

32, and as the plunger continues to move back a short distance further, the pawl is again raised and the ratchet turned thereby till another groove carrying another shell is positioned in front of another hole 10 in the 70 cylinder for insertion of another bag of explosive successively. As the open ends of the shells are placed close to the face of the cylinder, it is advisable to provide shallow grooves 10^a from the outside edges of the 75 holes in the cylinder to prevent the protruding fuses from becoming damaged as the cylinder revolves against the shell after the explosive has been properly placed therein.

The pulley shaft 52 for the bucket belt is 80 driven by bevel gear 58 thereon, meshing the gear 59 on perpendicular shaft 60 operated by gear 61, which is turned by gear 62 on the end of the main power shaft 23.

As the drum turns, the loaded shells drop 85 from the respective grooves into any suitable receptacle for packing.

A hole 63 is provided in the bottom of the chute near the top thereof to permit any 90 shells to fall therethrough, which are not suitably positioned to roll down the chute, and the top edges of the chute are widened out as 64 to press inward the ends of any of the shells which protrude too far to either 95 side.

We do not limit ourselves to the specific construction as herein shown, but reserve the right to make any changes deemed advisable for carrying out the objects of the invention.

Having described our invention, we claim:

1. A machine for loading firecracker shells, having a frame, a reciprocating plunger for compressing explosive material in the shells, a cylinder having tapered holes therethrough affixed on an axle, a drum having grooves on the periphery thereof, for retaining the shells for loading, the drum and cylinder being mounted having one end of each adjacent the other, and the holes in the cylinder coordinating with the grooves on the drum as they revolve, connecting gears for rotating the drum and cylinder, a chute and means for depositing the shells in the grooves as the drum revolves, means for holding the drum in a fixed position when the respective holes in the cylinder have been moved successively in front of the plunger until the plunger has pressed the explosive through the holes in the cylinder and into a shell on the drum and again withdrawn from the cylinder, and means for turning the drum and cylinder intermittently while the plunger moves continuously.

2. A machine for loading firecracker shells, having a frame, a reciprocating plunger for pressing sacks of explosive in the shells, means for moving and then holding the shells in front of the plunger, means for guiding the sacks into the shells, means

for compressing the sacks to suitable size while being moved forward by the plunger before entering the shells, means for conveying the shells to grooves on a rotatable drum in the path of travel of the plunger, a ratchet wheel and pawl for intermittently turning the drum as the plunger is reciprocated, the pawl mounted on an axle affixed to a yoke adjacent the ratchet wheel, the yoke alternately raised and lowered at predetermined periods by adjustable blocks on the plunger and means for conveying the movements of the blocks to the yoke.

3. A machine for pressing loads of explosive into tubular firecracker shells, having

means for holding the shells to be loaded in predetermined positions, means for conveying the shells to such positions, means for guiding sacks of explosive into one end of the shells, means for compressing the sacks 20 to suitable size for the shells, and means for forcing the compressed sacks into the shells to a predetermined position therein, the several parts of the machine being operated coordinately together.

In testimony whereof we affix our signatures.

DANIEL E. MULCAHY.
RAYMOND C. HITT.
